IP LLP

(57) **CLAIM**

The ornamental design for a hand-held power tool, as shown
and described.

DESCRIPTION

FIG. 1 is a perspective view of a hand-held power tool;
FIG. 2 is a front elevation view of the hand-held power tool;
FIG. 3 is a left side elevation view of the hand-held power
tool;

FIG. 4 is a rear elevation view of the hand-held power tool;
FIG. 5 is a right side elevation view of the hand-held power
tool;

FIG. 6 is a top plan view of the hand-held power tool; and,
FIG. 7 is a bottom plan view of the hand-held power tool.
The broken lines in the drawings illustrate portions of the
hand-held power tool that form no part of the claimed
design.

1 Claim, 7 Drawing Sheets
